SHEET METAL SHOVEL

Filed April 1, 1922

Inventor
JAMES M. ERVIN.

James M. Ervin

Attorney

UNITED STATES PATENT OFFICE.

JAMES M. ERVIN, OF DETROIT, MICHIGAN.

SHEET-METAL SHOVEL.

Application filed April 1, 1922. Serial No. 548,652.

To all whom it may concern:

Be it known that I, JAMES M. ERVIN, a citizen of the United States of America, residing at Detroit, in the county of Wayne and State of Michigan, have invented certain new and useful Improvements in Sheet-Metal Shovels, of which the following is a specification, reference being had therein to the accompanying drawings.

10 The usual practice in the manufacture of small shovels, and more particularly to those known as fire shovels, has been to blank out the sheet metal and then form the blank into the desired shape to provide a shovel and integral handle, but, in order to secure the necessary strength, it has been found necessary to use a comparatively heavy gauge of metal, and further, as said devices have been formed from a single 15 blank, a comparatively large sheet of metal has been necessary.

20 The object of the present invention is to so form up or shape a device of this character as to give the desired strength without the necessity for employing sheet metal of heavy gauge, and further to so construct the device that comparatively small pieces or scrap material may be utilized.

25 It is also an object to provide certain other new and useful features in the construction, all as hereinafter more fully described.

30 With the above and other ends in view, the invention consists in tapering the flange or rim of the blade into a tubular handle and strengthening the union of the handle and blade, by a hollow rib which forms a continuation of the tubular handle, projecting forwardly in the connection with the 35 blade within the area of the blade inclosed by its flange.

35 The invention further consists in providing a construction wherein the blade and handle portions are formed from separate blanks and which parts, when formed up, are so united as to provide a very strong and rigid connection between the blade and handle portions.

40 The invention also consists in certain other new and useful features in the construction, all as hereinafter more fully described and more particularly pointed out

in the appended claims, reference being had to the accompanying drawing in which—

Figure 1 is a plan view of a complete 55 shovel illustrative of the invention;

Fig. 2 is an inverted plan view of Fig. 1, with an end portion of the shovel blade broken away to shorten the figure;

Fig. 3 is a longitudinal sectional detail 60 substantially upon the line 3—3 of Fig. 2;

Fig. 4 is an end elevation of Figs. 1 and 2, showing the upper or handle end of the shovel with the handle in section;

Fig. 5 is a sectional detail substantially 65 upon the line 5—5 of Fig. 1; and

Fig. 6 is a detail plan view of a portion of a shovel illustrating a modified construction.

70 In order to secure the necessary strength to prevent bending and distortion, particularly where the handle unites with the blade, it has been found necessary to use sheet metal of a heavy gauge. In order to 75 secure lightness and cheapness, the present invention advances a construction which is such as to provide for the use of metal of a comparatively light gauge, the manner of forming the parts providing added stiffness and strength.

80 In the manufacture of certain devices, as for instance automobile bodies, large quantities of scrap material is produced. This material is usually of a comparatively light 85 gauge of metal and the pieces are too small to provide a blank from which an entire shovel may be formed. The present invention contemplates the utilization of this scrap material and in order that the small pieces may be used, a construction is contemplated wherein the blade portion of the 90 shovel and the handle portion are formed from separate blanks and so made that, when assembled, these parts are securely 95 united and interlocked in a manner to give a very strong and rigid construction, without the necessity for welding or otherwise intimately uniting the parts.

100 In Figs. 1 to 5 inclusive of the drawing, a construction is shown in which the blade 1 with its integral upturned flange or rim 2, is formed from a single sheet or blank of metal, and the tubular handle portion 3 is formed from a separate blank, the forward

end of the handle being extended and curved laterally to form a semi-tubular rib 4 with laterally extending flange portions 5 adapted to interlock with the flange 2 on the 5 blade. To firmly secure the handle portion to the blade, the lower or inner edges of the flanges 5 are turned outwardly or forwardly to form an integral bottom wall or flange 6 adapted to rest upon the rear or 10 heel portion of the blade 1 and this bottom wall is provided with a pair of lugs 7 which are extended through slots 8 in the blade to interlock the parts. The upper edges of the laterally extending flanges 5 of the 15 handle are turned over and formed down upon the upper edge portion of the rim 2 of the blade, as at 9. The flanges 5 of the handle which are integral with and taper into the tubular handle 3, are thus firmly 20 interlocked with the upper edge of the upstanding flange 2 of the blade, thus together with the lugs 7 firmly locking the handle to the blade without the necessity for intimately uniting the parts, as by riveting, 25 welding, etc. In uniting the handle with the blade, the shovel is placed within a suitable die and the parts are forced to place under a very heavy pressure, this die being so formed as to form or raise the portions 30 10 of the blade adjacent to the slots 8 above the plane of the body of the blade to permit the tongues or lugs 7 to lie within the recess thus formed at the lower side of the blade and give a smooth bottom surface, as 35 clearly shown in Fig. 5.

The semi-tubular extension 4 of the handle 3 provides a hollow strengthening rib projecting inwardly from the back wall or rear portion of the flange 2 of the blade and 40 by reason of the semi-tubular form of this rib, a very strong and rigid connection of the handle to the blade is secured at the point where sheet metal structures of this character are the weakest, this hollow rib forming 45 an arched bracing where the handle unites with the blade to prevent this portion from bending under the load applied to the blade and power for lifting the load applied to the handle.

50 In Fig. 6 of the drawing, a construction is illustrated wherein the blade and handle are formed from a single sheet metal blank, the flange 2 on the blade 1 tapering at the rear end of the blade, into the semi-tubular rib portion 4 which is an extension of the tubular handle, said rib curving downwardly or laterally from the end of the tubular portion 55 of the handle and projecting within the area enclosed by the rim or flange 2 of the blade. In this construction it is the semi-tubular strengthening rib 4 which provides the necessary stiffness to prevent the handle from bending at the point where it unites with the blade and its rim. The particular 60 hollow or semi-tubular form of the rib ex-

75 tension of the handle is the construction which gives rigidity and stiffness to the device and it is obvious that the particular form shown in the accompanying drawing is merely illustrative of the invention and may be modified within the scope of the appended claims, without departing from the spirit of the invention. I do not, therefore, limit myself to the particular form or arrangement shown.

Having thus fully described my invention, what I claim is:—

1. As a new article of manufacture, a sheet metal shovel comprising a blade portion, having a flange and a tubular handle portion, said tubular handle portion being formed with a hollow extension and laterally extending flanges integral with the hollow extension to engage over the flange of said blade portion, said laterally extending flanges forming means for securing the handle portion to the blade portion. 80

2. A sheet metal shovel comprising a blade portion having an upstanding edge flange and a handle portion comprising a tubular handle provided with a hollow extension having laterally extending flanges engaging the flange of the blade portion, said hollow extension forming a strengthening rib projecting beyond the flange of the blade portion and secured to the blade inside the flange. 90

3. A sheet metal shovel comprising a blade portion formed with an upstanding edge flange and with slots adjacent the heel of the blade, and a handle portion comprising a tubular handle formed with a hollow semi-tubular extension provided with laterally extending flanges to engage and interlock with the flange of the blade and provided 100 with lugs to engage the slots in the blade. 105

4. A sheet metal shovel comprising a blade having an upstanding edge flange, a tubular handle formed with a hollow laterally bent end extension with integral laterally 110 extending flanges having their upper edges bent over the edge of the blade flange, and means for securing the handle portion to the heel portion of the blade inwardly of its upstanding flange. 115

5. A sheet metal shovel comprising a blade formed from a sheet metal blank with an upstanding edge flange, and a handle portion formed from a sheet metal blank and formed into tubular form, with a laterally bent hollow semi-tubular end portion having integral laterally extending flanges, said flanges being formed to interlock with the upstanding flange of the blade and said handle portion and blade being formed to interlock adjacent the heel portion of the blade. 120

6. A sheet metal shovel comprising a blade portion formed from a sheet metal blank with an upstanding edge flange and pro- 125

vided with an opening adjacent its heel portion inwardly of said flange and a tubular handle portion formed from a sheet metal blank with a hollow laterally bent end portion provided with laterally extending integral flanges, and a bottom end wall, said laterally extending flanges being secured to the upstanding edge flange of the blade and

said bottom end wall being formed with a lug to engage the opening in the blade. 10

In testimony whereof I affix my signature in presence of two witnesses.

JAMES M. ERVIN.
